US00D974168S

(12) **United States Design Patent** (10) **Patent No.:** **US D974,168 S**
(45) **Date of Patent:** **** Jan. 3, 2023**

(54) **STANDING CLAMSHELL PACKAGING**

(71) Applicant: **Mariani Packing Co., Inc.**, Vacaville, CA (US)

(72) Inventors: **George Ignatius Sousa, Jr.**, El Macero, CA (US); **Stephen Sousa**, Davis, CA (US); **Christopher Allan Mariani**, Winters, CA (US); **Michael Andrew Mariani**, Winters, CA (US); **Joseph Steele Mariani**, Winters, CA (US)

(73) Assignee: **Mariani Packing Co., Inc.**, Vacaville, CA (US)

(**) Term: **15 Years**

(21) Appl. No.: **29/744,832**

(22) Filed: **Jul. 31, 2020**

(51) LOC (14) Cl. **09-03**

(52) U.S. Cl.

USPC **D9/429**; D9/420

(57) **CLAIM**

The ornamental design for a standing clamshell packaging, as shown and described.

DESCRIPTION

FIG. 1 is an isometric perspective view of the standing clamshell packaging in an open orientation;

FIG. 2 is a side elevation view of the invention in an open orientation;

FIG. 3 is a top plan view of the invention in an open orientation;

FIG. 4 is a bottom plan view of the invention in an open orientation;

FIG. 5 is a a first end elevation view of the invention in an open orientation;

FIG. 6 is a second end elevation view of the invention in an open orientation;

FIG. 7 is a standing front isometric perspective view of the invention in a closed orientation;

FIG. 8 is a standing rear isometric perspective view of the invention in a closed orientation;

FIG. 9 is a standing side elevation view of the invention in a closed orientation;

FIG. 10 is a bottom plan view of the invention in a closed orientation;

FIG. 11 is a second end elevation view of the invention in a closed orientation;

FIG. 12 is a side elevation view of the invention in a closed orientation;

FIG. 13 is a first end elevation view of the invention in a closed orientation; and,

FIG. 14 is a top plan view of the invention in a closed orientation.

The broken lines in the drawings represent unclaimed environmental subject matter and form no part of the claim.
